UNATTACHED SCREEN CLEAVER WHICH
CAN BE RENDERED INOPERATIVE

Leonard Johnson, Minneapolis, Minn., assignor
to Hart-Carter Company, Minneapolis, Minn.,
a corporation of Delaware

Application March 7, 1951, Serial No. 214,344

9 Claims. (Cl. 209—323)

1

My invention relates generally to improvements in grain separating machinery and more specifically to separating mechanism employing oscillatory screens in the separating or cleaning of grain.

More particularly, my invention relates to dockage testing equipment wherein a sample of grain from a selected quantity, such as a carload thereof, is tested to determine the percentage of foreign matter, such as seeds or grains of other types, etc., contained in said selected quantity.

An important object of my invention is the provision, in machines of the above type, of means for cleaning the separator screens between test runs in order to prevent grain from one tested quantity, which may lodge in the mesh of the separator screens or sieves, from carrying over into a second test run. To this end, I provide a plurality of resilient balls which are adapted to be impinged against the separator sieves in a manner to jar loose any particles which may be lodged in the sieves.

Another object of my invention is the provision of means for confining said balls in the cups during the test runs and for releasing said balls for sieve-cleaning operation between said test runs.

Dockage testers are generally provided with receivers in the nature of pans or trays which receive material separated from the grain during different stages of separation. Another object of my invention is the provision of means for preventing insertion of one of said receivers into receiving position in the dockage testing machine when said cleaning balls are free for cleaning movement in the cups containing the same, whereby to guard against the possibility of a false or inaccurate test.

The above and still further objects and advantages of my invention will become apparent from the following detailed specification, appended claims, and attached drawings.

Referring to the drawings, which illustrate the invention, and in which like characters indicate like parts throughout the several views:

Fig. 1 is a view in side elevation of a dockage tester incorporating my invention, some parts being broken away and some parts being shown in section;

Fig. 2 is an enlarged fragmentary view partly in plan and partly in section taken substantially on the line 2—2 of Fig. 1, some parts removed;

Fig. 3 is an enlarged fragmentary detail taken substantially on the line 3—3 of Fig. 1;

Fig. 4 is an enlarged transverse section taken on the line 4—4 of Fig. 1;

2

Fig. 5 is an enlarged fragmentary view in side elevation, as seen from the line 5—5 of Fig. 2.

Fig. 6 is a fragmentary section taken substantially on the line 6—6 of Fig. 4; and

Fig. 7 is a fragmentary view in side elevation, as seen from the line 7—7 of Fig. 2.

A preferred form of dockage tester is illustrated as comprising a frame structure 1 made up of laterally spaced frame members 2 and 3, a base member 4, and supporting legs 5. A plurality of shakers are mounted for oscillatory movements in the frame structure 1 in vertically spaced relationship, the uppermost thereof being indicated by the numeral 6 and adapted to receive grain or like material from a hopper or the like 7 mounted in the top portion of the frame 1. The shaker 6 is conventional in nature and separates a portion of the material fed thereto, that portion of the material in passing over the shaker 6 being delivered to a receiving pan or tray 8 that is supported on a shelf 9 extending transversely of the frame structure 1 and suitably anchored at its opposite ends to the opposite side frame members 2 and 3. Material passing through the shaker 6 is deposited on a second shaker, not shown, which delivers a portion of the material fed thereto to a receiver 10 suitably mounted on a shelf 11 similar to the shelf 9 and secured at its opposite ends to the opposite side frame members 2 and 3. The material passing through the second shaker, not shown, is delivered through a delivery chute 12 to the next lower shaker 13 from whence that portion of the grain which does not pass through the shaker 13 is delivered to a receiving tray 14 mounted on a shelf 15 identical in all respects to the shelf 11 and fastened to the frame structure in like manner. The grain which passes through the shaker 13 is delivered by means of a delivery chute 16 to the lowermost shaker 17 which is positioned to deliver larger particles of grain which do not pass through the shaker 17 to a receiving pan or tray 18 mounted on a shelf 19 identical to the shelves 11 and 15. The particles of grain passing through the shaker 17 are deposited in a receiving pan or tray 20 resting on the base member 4 directly below a delivery spout 21 depending from the shaker 17.

The shaker 6 and the second shaker, not shown, are oscillated by a conventional means, not shown, in the desired direction to perform their normal functions. The lower shakers 13 and 17 are in spaced parallel relationship and slope downwardly toward their respective receivers 14 and 18. Said shakers 13 and 17 are mounted for common oscillatory movements in opposite di-

55

rections by means including a pair of rock shafts 22 and 23 journaled in bearings 24 secured to the opposite side frame members 2 and 3, and supporting levers 25 located one each adjacent one of the corners of said shakers 13 and 17 and pivotally mounted thereto, the rear ones of said levers being pivotally secured to brackets 26 on the rear-ends of the shakers 13 and 17 and the forward ones of which are pivotally secured to bearing brackets 27 on the forward or delivery ends of the shakers 13 and 17. The levers 25 are secured intermediate their ends to the rock shaft 22 for common movements therewith, said movements causing oscillation of the shakers 13 and 17 in directions transversely off the direction of feed of the material in said shakers.

Each of the shakers 13 and 17 comprises shaker frames 28 having mounted therein screens or sieves 29 for the further separation of grain. The sieves 29 are preferably made from sheet material and perforated with apertures of desired size and spacing. Oscillatory movement imparted to the shakers 13 and 17 causes the material fed to the two said shakers to move downwardly under the action of gravity toward their respective receivers 14 and 18, the smaller particles dropping through the perforations in the sieves 29 thereof. Means for imparting oscillatory movements to the shakers 13 and 17 may be of any conventional type, one form thereof being fully described in my co-pending application Serial Number 214,243, filed of even date herewith, and entitled "Resilient Bumper Stop for Separator Screens."

Inasmuch as it is necessary to the accurate testing of grain samples to maintain the sieves 29 of the shakers 13 and 17 in a clean condition, it is important that said sieves be cleaned between each testing operation or at least if visual inspection of the screens shows grain lodging therein. For the easy and rapid removal of grains or other material caught in the sieves 29, I provide screen vibrating means in the nature of resilient rubber-like balls 30 each carried by a cup 31 in underlying spaced relation to the sieves 29. With particular reference to Figs. 1, 2, and 4, it will be seen that each of the shakers 13 and 17 is provided with a single row of cups 34 extending across the intermediate portion of its respective shaker intermediate the ends thereof and that there are preferably a plurality, as shown three in number, of said cups 31 to each of said shakers. The cups 31 each comprise an arcuate bottom wall 32, upwardly diverging end walls 33 which are tangential to the bottom wall 32 and side wall forming elements 34. Also, preferably and as shown, the side walls 34 extend substantially across the width of the sieves 29, one pair of side walls being common to all of the cups associated with one of said shakers 13 and 17. The diverging end walls are provided with flanges 35 that are spot welded or otherwise rigidly secured to the side walls 34, the end walls diverging toward opposite sides of the sieves 29, whereby when the shakers 13 and 17 are oscillated, the resilient balls 30 will be caused to roll upwardly on the diverging end walls 33 and impinge against the undersurface of the sieves 29 causing the same to vibrate and jar loose any grains that may be lodged in the perforations thereof. The arcuate bottoms 32 of the several cups 34 impart a rolling motion to the balls 30 so that when the balls 30 strike the sieves 29, the rolling action thereof will tend to reduce friction between the balls 30 and the sieves 29, resulting in reduced wear upon the balls 30 and consequent longer life thereof. With par-

ticular reference to Figs. 1, 4, 5, and 6, it will be seen that the side walls 34, at their lower edge portion, are flared outwardly, as indicated at 36, to provide therebetween and the arcuate bottom walls 32 relatively large openings 37 for the free passage of grain therethrough. At their opposite ends, the side walls 34 are secured to the shaker frames 28 by brackets 34'. With particular reference to Fig. 6, it will be seen that the openings 37 are of considerable less width than the diameter of the balls 30 so that there is no danger of the balls 30 dropping through said openings 37. The distance between the side walls 34 is such that the balls 30 are limited as to lateral movements within the cups 31.

In practice, the balls 30 are rendered inoperative during the testing of a selected quantity of grain through the machine. I, therefore, provide means for confining the balls 30 to the bottoms 20 of their respective cups, said means comprising a stop element in the nature of a stop plate 38 associated with each shaker 13 and 17. Each stop plate 38 is provided with a depending flange 39 to which is secured one end of a pair of laterally spaced pins or the like 40 which extend through opposite side wall forming elements 34, see Figs. 4-6, inclusive. The stop pins 40 are slidably mounted in the said wall elements 34 whereby to permit sliding movements of the stop plates 38 into and out of overlying relationship to the balls 30. A pair of spaced ears 41 project outwardly from the flanges 39 and are provided with slots 42 through which extend the offset intermediate portions 43 of cranks 44, journaled in the shaker frames 28 of the shakers 13 and 17. Rigidly secured by welding or the like to one end of each of the cranks 44 is one of a pair of relatively short crank-acting elements 45 which are pivotally connected to the opposite ends of a rigid adjustable link 46 extending generally vertically between the shakers 13 and 17. The rigid link 46 comprises a central element 47 having upper and lower extension elements 48 and 49, respectively, screw-threaded thereto and having pivotal connections with an adjacent crank-acting element 45, as indicated at 50 and 51, respectively.

A thrust rod 52 has a lower angularly disposed end portion 53 pivotally secured to the intermediate portion of the link element 47 and terminates at its other end in an eccentric 54 mounted on a control shaft 55 journaled adjacent its outer end in a bearing 56 secured to the side frame member 3. At its opposite end, the control shaft 55 is journaled in a pair of laterally spaced depending lugs 57 welded or otherwise rigidly secured to the shelf 9 at its central portion. A manually operated control knob 58 is rigidly secured to the shaft 55 laterally outwardly of the side frame member 3, manipulation of which will cause movement of the thrust rod 52 in directions to simultaneously move the stop plates 38 into and out of confining relationship with the resilient balls 30. When the control knob 58 is turned to the "off" position, illustrated in Fig. 7, the stop plates 38 are moved into overlying relationship to the balls 30, as indicated in Fig. 6. Obviously, when the control knob 58 is moved to the "on" position, the balls 30 are permitted to impinge against their respective sieves 29 when the shakers 13 and 17 are caused to oscillate.

When a test run has been made, the several receivers 8, 10, 14, 18, and 20 are removed from the machine and the contents thereof weighed or otherwise measured to determine the per-

centage and types of foreign material contained in the grain. During the removal of the several receivers, the control knob 58 is manually positioned to permit the cleaning balls 30 to operate. When the control knob 58 is in its "on" position, that is, when the balls 30 are free to impinge on the sieves 29, means now to be described are provided for preventing proper replacement of at least one of the receiving trays, namely the receiver 8, on its respective shelf. It will be noted, by reference to Figs. 1 and 2, that the several trays, when positioned on their respective shelves, are maintained in proper relationship to their respective shakers by means of hold-down elements 59. The said hold-downs 59 are generally U-shaped and have their opposite ends journalled in upstanding bearing lugs 60 and are biased in a direction to engage the top marginal edges of the several receiving trays by torsion springs 61 (see Fig. 2). A barrier element in the nature of a generally U-shaped barrier rod 62 is secured at one end to a transversely extending trunnion or the like 63 that is journalled in the depending lugs 57. A torsion spring 64 yieldingly urges the barrier rod 62 in a direction to move the free end portion 65 thereof upwardly through an opening 66 in the shelf 9 and into the space normally occupied by the receiving tray 8. A cam 67 mounted fast on the control shaft 55 intermediate the depending bearing lugs 57 engages the barrier rod 62 to swing the same downwardly against yielding bias of the torsion spring 64 when the control knob 58 is moved to its "off" position, and to permit the barrier rod to be moved upwardly by the spring 64 when the control knob is moved to its "on" position. Thus, if the operator neglects to set the control knob 58 to its ball-confining "off" position, the receiver 8 is barred from being properly positioned on the shelf 9 by the upwardly extended end portion 65 of the barrier rod 62. This arrangement indicates to the operator that he should turn the control knob to off-position before testing another sample.

Dockage testers, including the above described improvements comprising my invention, have been tested on a commercial basis and found to be completely satisfactory for the accomplishment of the objectives set forth; and, while I have shown and described a preferred embodiment of my invention, it will be understood that the same is capable of modification without departure from the spirit and scope of the invention as defined in the claims.

What I claim is:

1. In a device of the class described, a shaker frame, a sieve, means mounting said sieve on said shaker frame, means for imparting oscillatory movements to said shaker frame and said sieve, a plurality of cups associated with said frame and underlying said sieve in spaced relation thereto, said cups each having an arcuate bottom and upwardly diverging end walls which are tangential to said bottom, resilient balls in said cups, side wall forming elements in said cups limiting lateral movement of said balls therein, and means on said shaker frame movable into overlying relationship to said cups to retain said balls in the bottoms of their respective cups.

2. The structure defined in claim 1 in which said last-mentioned means comprises a stop plate mounted for sliding movements into and out of overlying relationship to said cups, and in further combination with manually operated means for imparting said movements to the stop

plate and including a crank journalled in said shaker frame.

3. In a device of the class described, a frame structure, a plurality of shaker frames in vertically spaced relationship, a sieve, means mounting said sieve on one of said shaker frames, means mounting said shaker frames in said frame structure for oscillatory movements with respect thereto, means for imparting oscillatory movements to said shaker frames and said sieve, a receiver for material passing over the other of said shakers, said receiver being movable into and out of receiving position in said frame structure adjacent the delivery end of said other shaker, a plurality of cups associated with said one of the shaker frames and underlying said sieve in spaced relation thereto, resilient balls in said cups, said balls being caused to impinge against said sieve responsive to oscillatory movements imparted thereto, means for confining said balls in the bottoms of their respective cups, said last-mentioned means comprising a stop element movable into and out of overlying relationship to said cups, manually operated mechanism for moving said stop element into and out of overlying relationship to said cups, a barrier element mounted on said frame structure for movements into and out of the area normally occupied by said receiver, and linkage associated with said manually operated mechanism for imparting movements to said barrier in a direction away from said area.

4. The structure defined in claim 3 in which said barrier element is yieldingly biased in the direction of said area and in which said linkage comprises a cam associated with said manually operated mechanism and engageable with said barrier to move said barrier against the yielding bias imparted thereto.

5. The structure defined in claim 3 in which each of said cups comprises an arcuate bottom, upwardly diverging end walls tangential to said bottom, and side wall forming elements spaced apart from the arcuate bottom to provide for the free passage of material therethrough.

6. In a device of the class described, a frame structure, a plurality of shaker frames in vertically spaced relationship, a sieve, means mounting said sieve on the lower of said shaker frames, means mounting said shaker frames in said frame structure for oscillatory movements with respect thereto, a receiver for material passing over the upper of said shakers, said receiver being movable into and out of material-receiving position in said frame structure adjacent the delivery end of said upper shaker, a plurality of cups associated with the lower shaker frame and underlying said sieve in spaced relation thereto, said cups each having an arcuate bottom and upwardly diverging end walls which are tangential to said bottom, resilient balls in said cups, said balls being caused to impinge against said sieve responsive to oscillatory movements imparted thereto, means for confining said balls in the bottoms of their respective cups, said last-mentioned means comprising a stop element movable into and out of overlying relationship to said cups, manually operated mechanism for moving said stop element into and out of overlying relationship to said cups, a barrier element mounted on said frame structure for movements into and out of the area normally occupied by said receiver, and means associated with said manually operated mechanism for imparting

movements to said barrier in a direction away from said area.

7. The structure defined in claim 6 in which said stop element is in the nature of a stop plate mounted for sliding movements into and out of overlying relationship to said cups and the balls contained therein, and in which said manually operated means includes a crank journaled in the lower of said shaker frames and operatively associated with said stop plate.

8. In a device of the class described, a frame structure, a plurality of shaker frames in vertically spaced relationship, a plurality of sieves, means mounting said sieves one each on one of said shaker frames, means mounting said shaker frames in said frame structure for oscillatory movements transversely of said frame structure, a plurality of cups associated with each of said frames and underlying the sieves thereof in spaced relation thereto, said cups each having an arcuate bottom and upwardly diverging end walls which are tangential to said bottom, resilient balls in said cups, side wall forming elements in said cups limiting lateral movement of said balls therein, a pair of stop plates one each associated with each of said sieves and mounted for sliding movements into and out of overlying relationship to said cups, crank elements pivotally secured to said shakers and associated one each with one of said stop plates, linkage connecting said cranks whereby said stop plates are movable simultaneously in the same direction, and manually operated mechanism for imparting movements to said linkage to move said stop plates, said manually operated mechanism comprising a single

control knob, an eccentric mounted for rotation with said control knob, and a rigid thrust member connected at its opposite ends to said eccentric and said linkage.

9. In a device of the class described, a shaker frame, a sieve, means mounting said sieve on said shaker frame, means for imparting oscillatory movements to said shaker frame and said sieve, a plurality of cups associated with said frame and underlying said sieve in spaced relation thereto, said cups having an arcuate bottom and upwardly diverging end walls which are tangential to said bottom, cross-sectionally round resilient rolling bodies contained one each in each of said cups, side wall forming elements in said cups limiting lateral movements of the bodies therein, and means on said shaker frame movable into overlying relationship to said cups to retain said bodies in the arcuate bottoms of said cups.
